(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a left side view thereof;

FIG. 4 is a right side view thereof;

FIG. 5 is a top plan view thereof where the bottom plan view is a mirror image;

FIG. 6 is a front perspective view thereof showing an example of the usage of the subject design; and,

FIG. 7 is a rear perspective view thereof showing an example of the usage of the subject design.

The broken lines in FIGS. 6 and 7 show non-claimed examples of possible displayed subject matter and form no part of the claimed design.

1 Claim, 7 Drawing Sheets
